SEWING MACHINE

Carl F. Whitaker, Beverly, Mass., assignor to
United Shoe Machinery Corporation, Flemington, N. J., a corporation of New Jersey

Application March 11, 1941, Serial No. 382,677

12 Claims. (Cl. 112—62)

The present invention relates to shoe sewing machines, and more particularly to improvements in machines for sewing a welt to the marginal portion of an outsole before either is attached to the shoe upper.

In the manufacture of cemented shoes, it is the usual practice to cut the outsole to substantially its finished size, leaving practically no margin to be trimmed away. In order that the finished shoe may resemble in appearance a shoe having a Goodyear welt outseam, there is secured to the outsole, before the insole and upper are attached, a welt extending around the fore part of the shoe, the welt having its grain surface exposed and being secured to the margin of the outsole by a line of stitches. To permit the welt to lie flat around the curved edges of the outsole, there is frequently employed a welt having a reduced or "feathered" edge, which edge extends inwardly of the sole edge, the unreduced portion of the welt lying along the margin of the outsole. The inclined surface of the welt thus serves as a seat for the upper, while the roughened surface resulting from the skiving is of value in securing a firm bond in the subsequent cementing of the upper to the outsole.

When such an outsole is assembled with a lasted upper, the molding operation results in curving of the outsole to conform to the curved bottom of the last. As a consequence, the edge surfaces of the outsole no longer lie parallel, but instead are inclined inwardly, so that the sole edges are visible from above. In the subsequent trimming or rounding operation to restore the edges of the sole to parallelism, care is necessary to avoid cutting into the stitches adjacent the tread side of the outsole, since the stitches, as well as the sole edge surfaces, become inclined during the molding of the outsole.

To avoid this difficulty, there has been devised the method and a machine for sewing a welt and outsole together wherein the stitches are inclined with respect to the flat outsole, so that upon molding of the sole to the lasted upper, the stitch lines through the work will be directed into substantial parallelism, permitting the sole edges to be finished to proper shape without risk of cutting into the stitches adjacent the tread face of the sole. A machine for stitching in the above manner is disclosed in U. S. Letters Patent to Hopkins and Bertrand, No. 2,233,413, issued March 4, 1941. In said patent, the machine employed for the sewing operation is provided with a work support or table fixed at such an angle

with respect to the path of the needle and awl through the work that the stitches are substantially inclined with respect to the outsole when flat.

5 The aforesaid machine is well suited to the sewing of one weight or thickness of sole, for example, the relatively light weight outsole for women's shoes. If, however, it is desired to sew various weights of outsoles on a single machine, it becomes necessary to provide different work tables arranged to make different angles with the path of needle and awl through the work, in order that the proper inclination of the seam may be obtained in every instance. Thus, a 10 table that provides the proper angle for women's outsoles causes, on heavy outsoles for men's shoes, the stitches to be thrown inwardly an excessive distance on the tread face of the sole, as well as drawing the outsole against the edge gage with such force as to cause frequent 15 breakage of the gage.

The present invention has as an object, therefore, the provision in a machine for sewing a welt to the margin of an outsole, of a work table and presser foot arranged to permit adjustment 20 of the angle which the work makes with the path of the needle therethrough, whereby the desired inclination of the stitches appropriate to the thickness of the work may be obtained.

25 In sewing the outsole to the welted upper in a Goodyear welt shoe, it is generally necessary, when sewing along the shank portion, to tilt the shoe considerably so as to avoid contact of the needle with the upper just above the welt. As a result, the line of stitches appears on the bottom of the shoe spaced somewhat farther in 30 from the sole edge along the shank portion than around the fore part of the sole. In order that this more or less characteristic appearance of a Goodyear welt outseam may be simulated as closely as possible in a cemented-type shoe, it is desirable that the line of stitches by which the welt is attached to the outsole be spaced somewhat further from the edge along the shank 35 of the outsole than around the fore part of the shoe. While such change in spacing during sewing results merely by tilting the shoe bodily during sewing in the case of the Goodyear shoe since the shoe, being lasted, is handled as a unit, the assembly of the welt and outsole of a cemented shoe requires that the two parts be accurately and independently guided between the clamping surfaces of work support and presser foot with the margin of the welt at all times in proper 40 relation to the margin of the outsole.

It is, therefore, another object of the invention to provide, in a machine for sewing a welt to the margin of an outsole prior to the attachment of the upper, simple and improved mechanism for guiding the welt and outsole to the sewing point with their edges in accurate predetermined relationship, said mechanism being adjustable during sewing to change the spacing of the seam relative to the margin of the assembly while nevertheless maintaining accurately said predetermined relationship of the parts.

Since it is desirable in fairstitching a welt to an outsole that a groove be formed in the tread face of the outsole in which the stitches may be laid, the presser foot is customarily provided with a sole grooving knife or point arranged to engage and groove the work immediately in advance of the sewing point. In order that, in the machine of the present invention, the groove may be formed in accurate alignment with the seam line for work of various thicknesses and with different adjustments of work angle, the present invention has as a further object the provision in the aforesaid machine of novel and improved means for readily effecting bodily adjustment of the presser foot transversely of the seam line, whereby, after such other adjustments as may be required have been made, the grooving point may quickly be brought into alignment with the seam line without disturbing the previously made adjustments.

In the accompanying drawings illustrating the several features of the invention, Figure 1 is a view in right side elevation of the portion of a lock stitch sewing machine adjacent the sewing point, with the work table and presser foot of the invention adjusted to support the work at a substantial inclination to the needle path; Figure 2 is an oblique view, partly broken away, of the work table together with the welt guide and edge gage; Figure 3 is a detail right side view of the presser foot and a portion of its supporting arm; Figure 4 is a right side view of the work table and its adjustable welt guide and edge gage; Figure 5 is a front elevation of the parts shown in Figure 4; Figure 6 is a top plan view of the same; Figure 7 is a detail view, looking from the left, of the angularly adjustable connection between the work table and its supporting bracket; Figure 8 is a detail sectional view of a portion of a welt and outsole before attachment to a lasted upper, showing the inclination of the stitch line with respect to the tread face; and Figure 9 is a plan view of a portion of the tread face of a welted outsole as sewn on the machine of the invention, illustrating the greater spacing of the seam line from the edge of the shoe along the shank portion thereof compared with around the toe, as provided by the adjustable edge gage and welt guide.

The invention is embodied by way of illustration in a lock stitch outsole shoe sewing machine of the same general type as that illustrated in U. S. Letters Patent to Fred Ashworth, No. 1,169,909 dated February 1, 1916. The machine employs a curved hook needle 42 and a curved awl 14 actuated alternately to enter and withdraw from the work along a curved path, indicated by dot and dash line 16.

To support the work properly for sewing the welt 18 to the outsole 20, a work table 22 is employed having a top surface 24 of substantially greater area than the conventional work table. Support is thereby afforded to the outsole to prevent bending and distortion under the inward pressure which the operator may be required to

exert against the outer edge of the sole to maintain the work in proper position as it is being sewn, as more fully set forth in Patent No. 2,233,413 above referred to. A slot 26 at the rear of the work table provides passage for the awl and needle.

To enable the welt and sole to be sewn together by a seam having an inclination to the sole tread surface appropriate to the thickness of the particular work being sewn, the work table 22 is mounted on the machine frame with provision for angular adjustment relative to the needle path at the sewing point. To this end, the work table is carried by a bracket 30 having a rearwardly extending arm arranged to be bolted to the machine frame, 32 in the place of the usual work support. At its forward end the bracket is provided with a vertical face 34 in which is formed an arcuate channel or guideway 36. The work table at its left side has a depending flange portion 38 the clamping surface of which is complementary in shape to that of the bracket, being provided with an arcuate shoulder 40 which is received within the guideway 36. An arcuate slot 42 in the bracket affords a passage for clamping bolts 44 by which the work table may be secured in adjusted position.

In order that changes in the seam inclination through adjustment of the work table angle may not appreciably disturb the spacing of the seam line from the edge of the work on the welt side thereof, the work table is arranged to be adjusted about a fixed center which is substantially coincident with the point of intersection of the needle path 16 with the surface of the work table, such point being indicated at 46. Accordingly, the arcuate guideway 36 in the supporting bracket 30 and the complementary arcuate shoulder 40 in the work table are concentrically disposed with respect to point 46, so that upon loosening bolts 44, the work table may readily be tipped to the appropriate angle without effect on the seam spacing on the welt side, (dimension *a* in Figure 8).

Adjustment of the inclination of the presser foot 48 is likewise provided enabling the work to be clamped effectively between substantially parallel surfaces. Such adjustment is provided by forming the presser foot arm in two parts, 50 and 52, the presser foot being secured to part 50, with the major portion 52 of the arm extending rearwardly to its supporting shaft hereinafter referred to. The two parts have cooperating clamping surfaces which include an arcuate channel 54 in the arm 52 and a complementary arcuate shoulder 56 at the upper end of the portion 50, with a clamping bolt 58 passing through slot 60. The radius of curvature of channel 54 and shoulder 56 is such that the center about which the presser foot swings, during its adjustment for work inclination, lies on the clamping face of the presser foot substantially in alignment with the sole grooving point 62 (see Figure 3). Since this point, through bodily adjustment of the presser foot arm as hereinafter described, is caused to align accurately with the seam line on the tread face of the sole, the adjustment of the presser foot takes place about a center which is substantially coincident with the sewing point on the tread face of the work, in the same manner that the adjustment of the work table is effected about a center coinciding with the sewing point on the other face of the work, in this case the surface of the welt.

The sole and welt are guided independently

to the sewing point in accurately maintained relationship by guiding mechanism which, though arranged to permit adjustment in the course of sewing a seam, is nevertheless carried entirely by the work table so that adjustment of the latter for work inclination is in no way hindered. To this end, the work table is provided with a gage-carrying cross slide 70 which is movable in guideways 72 transversely of the direction of work feed. The rear portion of the slide is formed with a gradually sloping surface 74 which extends upwardly toward the sewing point from right to left, (Figures 2, 5, and 6), the portion of the slide devoted to this sloping portion being substantially wider, transversely of work feed, than a welt of average width. A cover plate 76 secured by screws 78 is received within a shallow channel in the top of the slide to lie flush with the surface of the work table, the portion 79 of the cover which extends over the surface 74 being triangular in cross section (see Figure 2) so that the under surface thereof lies parallel to upwardly sloping surface 74 to define the top of the welt passage.

In order that different sizes and types of welts may be accommodated, there is arranged within the inclined space between slide and cover plate a welt guide which is not only transversely adjustable, but also readily removable to permit the use of other guides each especially suited to a given welt. The welt guide, illustrated at 80, may conveniently be formed of sheet metal bent into a channel of width appropriate to the welt to be guided. The sides of the channel are cut at an angle, as at 82, to lie flush with the work table surface while affording guidance to the welt substantially to the sewing point. The guide 80 is secured in position by means of an integrally formed forked ear 84 which is adapted to be clamped to the side of the slide 70 at the rear thereof.

The edge gage for guiding the sole to the sewing point is likewise carried by the cross-slide 70 for movement therewith, and is provided with a work engaging portion 86 disposed to the rear of the sewing point, the face being substantially normal to the work table surface and curved slightly away from the line of feed on either side of the sewing point, (see plan view, Figure 6). From its work engaging portion the gage extends to the right and rear to an integrally formed lug 88 provided with a horizontal slot 90 through which passes a clamping bolt 92 by which the edge gage and the welt guide as well are secured to the cross slide, the forked ear 84 of the welt guide being clamped beneath lug 88. Thus, by loosening bolt 92, the edge gage and welt guide may be independently adjusted relative to one another and to the cross slide to insure proper guidance of welt and sole to the sewing point in the desired relationship. Likewise, the removal of one type or size of welt guide and replacement by another is facilitated through the use of the single clamping bolt and relative adjustability of the parts.

The cross slide is adjusted along its guideway during sewing to change the spacing of the seam from the margin of the work by mechanism actuated by a handle 94 which extends into a position to be grasped and actuated conveniently by the operator. The handle 94 forms one arm of a bell crank lever 96 pivotally mounted on a stud 98 secured in the underside of the work table. The other arm, at its outer end, is provided with a straight slot 100 through which extends a stud 102 carried by the cross slide 70 on its underside. A spring washer 104 with lock nuts 106 be-

low affords sufficient friction to prevent accidental movement of the slotted arm relative to the stud.

Since the slot extends in a direction substantially perpendicular to a line drawn through the pivotal center of the bell crank and across one end of the slot, or, in other words, is tangential rather than arcuate, it is evident that rotation of the lever about its center causes a small and accurately controllable movement of the slide along its guideway across the work table. For normal spacing of the seam, the handle may be set in the position shown in Figure 6 to provide a seam spacing such as shown by dimension c in Figure 9. Upon coming to the shank portion of the sole, the operator will gradually push the handle rearwardly to move both edge gage and welt guide back from the sewing point slightly, to increase the seam spacing to that represented by dimension d in Figure 9. The amount of increase is limited by an adjustable stop screw 108 secured by lock nut 110 in a fixed portion 112 of the work table and adapted to engage an extension 114 of the bell crank lever 96. The seam spacing, when the lever is in its forward position, Figure 6, is determined by the setting of the gage and guide on the cross slide.

In order that the grooving point 62 carried by the presser foot may be made to align properly with the sewing point on the tread face of the work, it is necessary that the presser foot be bodily adjustable transversely of the seam line. Such adjustment may not only be required upon a change from one presser foot to another, but also, in certain cases, as a result of shifting to work of different thickness, involving a resetting of the inclination of work table and presser foot. In the machine of the present invention, this adjustment is effected by journaling the presser foot arm 52 and its integrally formed lever 116 upon a fulcrum pin 118 having an eccentric portion 120 which may be clamped within a split sleeve 122 in the machine frame by stud 124. The presser foot arm is journalled upon the portion 126 of the pin, and also upon the reduced end portion 128 concentric therewith, and is actuated to clamp and unclamp the work by connections to the lever 116 of the same general type as shown in Ashworth Patent No. 1,169,909 above referred to. Upon loosening stud 124, the pin 118 may be rotated by means of a screw driver or like tool inserted in slot 130 to effect bodily displacement of the axis of rotation of the presser foot arm, and hence adjust the presser foot and grooving point transversely of the direction of the seam line. The reduced portion 132 of the head of the pin 118 limits the rotation thereof to the 130° needed for the full range of adjustment, the head of the screw 134 which secures upstanding arm 136 to the presser foot lever 116 serving as a stop.

Having thus described the invention, what is claimed is:

1. A lockstitch sewing machine for attaching a welt to the marginal portion of an unattached outsole having, in combination, a curved needle and a curved awl, means for guiding the welt and outsole to the sewing point, and a work table supported on the machine with provision for tilting adjustment about a center substantially concentric with a point on the needle path adjacent the intersection of the supporting surface of the work table therewith to permit adjustment of the inclination of the welt and outsole to the path of movement of needle and awl through the work,

whereby the relative spacing of the seam lines on opposite sides of the work from the margin thereof may be adjusted.

2. A lockstitch sewing machine for attaching a welt to the marginal portion of an unattached outsole having, in combination, a curved needle and a curved awl, means for guiding the welt and outsole to the sewing point, and work clamping means for supporting the welt and outsole adjacent the sewing point, said clamping means comprising a work table and a presser foot, each supported on the machine with provision for tilting adjustment about a center substantially concentric with a point adjacent the intersection of its work engaging face with the needle path to permit adjustment of the inclination of the welt and outsole to the path of movement of the needle and awl through the work while enabling the work engaging faces of work table and presser foot to lie substantially parallel during operation of the machine, whereby to provide adjustment of the inclination of the line of stitches relative to the tread face of the outsole.

3. A lockstitch sewing machine for attaching a welt to the marginal portion of an unattached outsole having, in combination, a curved needle and a curved awl, means for guiding the welt and outsole to the sewing point, and a work table supported on the machine with provision for adjustment of the inclination of its work supporting surface to the path of movement of the needle and awl through the work, said work table being guided to tilt about an axis parallel to the axis of needle and awl, the center of said axis of tilt being substantially concentric with a point on the needle path adjacent the surface of the work table whereby adjustment of the inclination of the line of stitches relative to the tread face of the work may be effected without appreciable displacement of the work from the sewing point.

4. A lockstitch sewing machine for attaching a welt to the marginal portion of an unattached outsole having, in combination, a curved needle and a curved awl, means for guiding the welt and outsole to the sewing point, and work clamping means for supporting the welt and outsole adjacent the sewing point including a presser foot, and a work table and means for supporting the same on the machine, and connections between the work table and its supporting means comprising cooperating arcuate guideways whose center is substantially concentric with the point of intersection of the needle path with the work supporting surface of the work table to permit adjustment of the inclination of said work supporting surface of the work table relative to the needle path without appreciably altering the position of the sewing point along the needle path.

5. A lockstitch sewing machine for attaching a welt to the marginal portion of an unattached outsole having, in combination, a curved needle and a curved awl, means for guiding the welt and outsole to the sewing point, and work clamping means for supporting the welt and outsole adjacent the sewing point, said means including a work table and a presser foot, and supporting means therefor, connections between the work table and presser foot and their respective supporting means including arcuate guideways disposed substantially concentrically with respect to the sewing point whereby adjustment of the inclination of the work engaging surfaces of work table and presser foot to the path of the needle and awl through the work may be effected while

maintaining substantial parallelism of said surfaces and without causing appreciable displacement of the work relative to the sewing point.

6. A lockstitch sewing machine for attaching a welt to the marginal portion of an unattached outsole having, in combination, a curved needle and a curved awl, means for guiding the welt and outsole to the sewing point, and work clamping means for supporting the welt and outsole adjacent the sewing point, including a presser foot provided with a grooving point projecting below the work engaging face thereof for forming a seam receiving channel in the tread face of the outsole, and means for supporting the presser foot including connections comprising cooperating arcuate guideways disposed substantially concentrically with respect to said grooving point whereby the adjustment of the inclination of the work engaging face of the presser foot to the path of the needle and awl through the work may be effected about the sewing point as a center.

7. A lockstitch sewing machine for attaching a welt to the marginal portion of an unattached outsole having, in combination, a curved needle and a curved awl, work clamping means for supporting the welt and outsole adjacent the sewing point, said work clamping means including a work table mounted to permit adjustment of the inclination of its work supporting surface to the path of movement of the needle and awl through the work, whereby to change the relative spacing of the seam lines on the welt and tread sides of the work from the margin thereof, and means for guiding the welt and outsole to the sewing point, adjustable during the sewing of a seam irrespective of the inclination of the work table, to vary the spacing of the line of stitching from the edge of the sole as the sewing progresses around the work.

8. A lockstitch sewing machine for attaching a welt to the marginal portion of an unattached outsole having, in combination, a curved needle and a curved awl, work clamping means for supporting the welt and outsole adjacent the sewing point, said work clamping means including a work table mounted to permit adjustment of the inclination of its work supporting surface to the path of movement of the needle and awl through the work, whereby to change the relative spacing of the seam lines on the welt and tread sides of the work from the margin thereof, and means for guiding the welt and outsole to the sewing point including mechanism under the control of the operator and carried entirely by said work table for adjusting the guiding means during sewing to vary the spacing of the line of stitching from the edge of the sole.

9. A lockstitch sewing machine for attaching a welt to the marginal portion of an unattached outsole having, in combination, a curved needle and a curved awl, work clamping means including a work table for supporting the welt and outsole adjacent the sewing point, and means for guiding the welt and outsole to the sewing point comprising a sole edge gage and a welt guide, a slide mounted in the work table and carrying the guide and gage, said slide being movable transversely of the axis of needle and awl to vary the spacing of the line of stitching from the edge of the sole, and means carried by the work table and extending into a position to be grasped by the operator for adjusting the slide in the work table.

10. A lockstitch sewing machine for attaching a welt to the marginal portion of an unattached outsole having, in combination, a curved needle

and a curved awl, work clamping means including a work table for supporting the welt and outsole adjacent the sewing point, and means for guiding the welt and outsole to the sewing point comprising a sole edge gage and a welt guide, a slide mounted in the work table for movement transversely of the axis of needle and awl, means for securing the gage and guide to the slide in independently adjustable position, and means carried by the work table for adjusting the slide during sewing to vary the spacing of the line of stitching from the edge of the sole while maintaining the relative positions of sole and welt.

11. A lockstitch sewing machine for attaching a welt to the marginal portion of an unattached outsole having, in combination, a curved needle and a curved awl, work clamping means including a work table for supporting the welt and outsole adjacent the sewing point, and means for guiding the welt and outsole to the sewing point including a slide carrying said guiding means and mounted in the work table for movement transversely of the axis of needle and awl, said slide having a passage therein upwardly inclined

toward the sewing point, and a welt guide demountably mounted in said passage and adjustable relative to the slide in the direction of movement thereof.

- 5 12. A lockstitch sewing machine for attaching a welt to the marginal portion of an unattached outsole having, in combination, a curved needle and a curved awl, means for guiding the welt and outsole to the sewing point, and work clamping means for supporting the welt and outsole adjacent the sewing point, said clamping means comprising a work table and a presser foot supported on the machine with provision for adjustment of the inclination of their work engaging surfaces to
- 10 15 the path of movement of the needle and awl through the work, the presser foot having a grooving point projecting below the work engaging face thereof for forming a seam receiving channel in the tread face of the outsole, and means
- 15 20 for effecting bodily adjustment of the presser foot transversely of the axis of needle and awl to align the grooving point with the seam line.

CARL F. WHITAKER.
